UNITED STATES PATENT OFFICE.

MALTIAH B. BLACKMER, OF PLYMOUTH, MASSACHUSETTS.

PUNCH.

SPECIFICATION forming part of Letters Patent No. 350,968, dated October 19, 1886.

Application filed December 5, 1885. Serial No. 184,837. (No model.)

To all whom it may concern:

Be it known that I, MALTIAH B. BLACKMER, of Plymouth, in the county of Plymouth and State of Massachusetts, have invented certain 5 new and useful Improvements in Punches, of which the following is a specification.

This invention has for its object to provide an improved means for holding a small punch or punches used to perforate steel shanks for 10 boot and shoe soles.

The invention consists in a punch composed of a rod of indefinite length combined with two jaws, which are caused to clamp said rod by set-screws or other pressure devices inserted in a holder that contains said jaws and rod, as I will now proceed to describe.

Of the accompanying drawings, forming a part of this specification, Figure 1 represents a vertical section of a punch and its holding 20 devices embodying my invention. Fig. 2 represents a section on line x x , Fig. 1. Figs. 3 and 4 represent modifications.

In the drawings, a represents the punch, which is a cylindrical rod or wire of any desired length.

b represent the two jaws, each of which is preferably made in a separate piece, preferably semicircular in cross-section. Said jaws have grooves in their flat inner sides, which 30 partially receive the rod or punch a , as shown in Fig. 2.

c represents the holder, which is suitably affixed to a cross-head or plunger in an organized punching-machine, and has a socket 35 formed to receive the jaws b , and one or more set-screws or other pressure devices, whereby the jaws may be clamped against the rod or punch and secured to the holder.

It will be seen that by loosening the set- 40 screws the punch may be raised or lowered, either with the jaws or independently thereof, the punch being loosened or released by the

jaws when the screws are loosened; hence the punch can be adjusted downwardly as fast as it is worn at its operating end, and securely 45 held at any point to which it is adjusted. The jaws may also be adjusted to and held at any desired height by the same means, so that after the punch is so reduced in length that it cannot be further adjusted independently to compensate for wear, the jaws may be adjusted 50 downwardly until the portion of the punch projecting from them is worn out.

The jaws may be provided with two grooves, so as to hold two punches.

The jaws may be rectangular in cross-section instead of semi-cylindrical.

My invention is not limited to punches for perforating steel shanks, but may be used for general punching wherever a small hole is to 60 be made in metal by a reciprocating punch.

A modification is shown in Figs. 3 and 4, in which only one movable clamping jaw or part is used, the other clamping part being one side of the socket in the holder c . Both clamping 65 surfaces are grooved, as in the examples previously described.

I claim—

A punch consisting of a rod, a , of uniform diameter, formed to act as a punch at any portion of its length, two jaws having grooved faces embracing the rod, a holder for said jaws, and a set screw or screws which hold the jaws and rod and permit said rod to be adjusted to compensate for wear thereof, as set 70 forth.

In testimony whereof I have signed my name to this specification, in the presence of two subscribing witnesses, this 12th day of November, 1885.

MALTIAH B. BLACKMER.
